(57) **CLAIM**

The ornamental design for a faucet handle, as shown and described.

DESCRIPTION

FIG. 1 is a front view of a faucet handle showing my new design;

FIG. 2 is a left side view thereof;

FIG. 3 is a rear view thereof;

FIG. 4 is a right side view thereof;

FIG. 5 is top view thereof;

FIG. 6 is a bottom view thereof;

FIG. 7 is a front isometric view thereof; and,

FIG. 8 is a rear isometric view thereof.

Features shown in broken lines form no part of the claimed design.
